UNITED STATES PATENT OFFICE.

GEORGE F. RADCLIFFE AND JOHN C. SLUTZ, OF KANSAS CITY, KANSAS.

CAR-FENDER.

SPECIFICATION forming part of Letters Patent No. 600,596, dated March 15, 1898.

Application filed June 14, 1897. Serial No. 640,646. (No model.)

To all whom it may concern:

Be it known that we, GEORGE F. RADCLIFFE and JOHN C. SLUTZ, citizens of the United States, residing in Kansas City, county of Wyandotte, and State of Kansas, have invented certain new and useful Improvements in Car-Fenders, of which the following is a specification, reference being had therein to the accompanying drawings.

10 Our invention relates to improvements in car-fenders.

The object of our invention is to provide a car-fender which is simple in construction, easily and quickly operated, not liable to get 15 out of order, and one which may be readily adapted to any of the ordinary types of street-cars.

In the construction employed by us the fender is of the scoop type—that is, the frame-work comprising the apron is of a scoop shape. The rear end of the apron is pivoted in bearings carried by the car and the front end is supported normally several inches above the track, mechanism hereinafter described being provided whereby the motorman may, as occasion requires, drop the forward end of the fender to the track.

20 Our invention comprises, further, certain novel details of construction hereinafter fully described and claimed.

In the accompanying drawings, illustrative of our invention, Figure 1 represents a vertical sectional view. Fig. 2 represents a side elevation with a portion of the car broken away, so as better to disclose some of the fender mechanism. Fig. 3 represents a top view with some of the car and parts of the fender removed. Fig. 4 represents a top view of the catch-bar and a portion of the platform. Fig. 25 5 represents a vertical sectional view showing the modified form attached to a grip-car. Fig. 6 represents a top view of the supplemental apron and rock bar or shaft G and some of the parts connected therewith. Fig. 40 7 represents a side elevation of what is shown in Fig. 6.

Similar letters of reference indicate similar parts throughout the several views.

Owing to its lightness and comparative 45 strength, I prefer to make the fender-frame of tubing.

A indicates the frame of the fender, which

comprises a horizontal section of piping which reaches transversely across the car-track and which is located some distance in front of the 55 dashboard of the car. Rearwardly extending from each outer end of this section is a horizontally-disposed arm of the same material, the rear ends, at some distance in the rear of the dashboard and in front of the forward 60 truck-wheels, being inwardly and upwardly turned, the extreme rear end being pivoted in a bearing B, secured to the under side of a longitudinal stringer C, which forms part of the platform of the car.

65 D indicates the flooring of the car, and D' the dashboard thereof.

E indicates a vertical post secured one at each side of the frame A at its lower end, the upper end of the post E being inwardly turned 70 and pivotally fitted in a slot F of a forwardly-projecting arm F', with which each end of a horizontal rock-shaft G is provided. The said rock-shaft G extends transversely across and under the car-platform, to which it is secured by means of the bearings I, which are secured, respectively, to the under side of the car-sills X near the forward end thereof. Near the center of the rock-shaft G is formed 75 therein a U-shaped crank-arm H, to which is pivoted the lower end of an upwardly-projecting catch-bar J, which extends upwardly through an opening provided therefor in the car-floor. The upper end of the catch-bar J is provided with a transverse opening in which 80 is fitted one end of a link K, adapted to be seized with the hand for the purpose of pulling the catch-bar upwardly and rocking the rock-shaft G, so as to elevate the forward end 85 of the fender-frame A.

90 Secured to the upper side of the floor D is a flat plate M, which is provided with a slot in which the catch-bar J is vertically movable. The catch-bar is provided with a notch L in its rear edge, which is adapted when the 95 catch-bar is raised to its highest position to engage the plate M at the rear end of the slot in the said plate. A curved spring N is secured to the under side of the car-floor in such a position that it will bear against the forward edge of the catch-bar when the catch-bar is in the raised position and force the upper end of the said catch-bar rearwardly, so that the notch L therein will engage the plate M and 100

prevent the catch-bar from moving downwardly. In order to prevent the accidental displacement of the catch-bar when it is in the raised position and thus allow the fender 5 to fall at its forward end, a small wedge R, adapted to fit into the slot in the plate M in front of the catch-bar when the notch in the catch-bar is engaged with the plate M, is provided. The wedge R may be made secure 10 against loss by attaching it to the car, as by means of a chain P, secured at one end to the wedge and at the other end to an eye O, which is secured to the dashboard.

Secured to the forward end of the fender-frame A, at a point over each track-rail W, 15 is a shoe S, comprising a horizontally-disposed plate having its forward end upwardly curved. The function of the shoes S is to guard the forward end of the fender against contact 20 with guard-rails which are higher than the track-rails.

Connecting the two parallel sides of the fender-frame A, near the center and rear ends, respectively, are two tubes U and V, which 25 serve the functions of equalizing-bars. A series of rods T connect the pipe U with the forward end of the fender-frame. A similar series of rods connect the two pipes U and V. These rods form a screen upon which may 30 rest any object which is picked up by the fender. The rods T may be replaced by ropes or wire-netting, if desired.

Two brace-wires Y are secured, respectively, to the rear ends of the upwardly-extending 35 arms of the fender-frame A and pass thence to the vertical posts E, around which they are wound, and pass thence to the forward end of the fender-frame, to which the forward ends are secured.

40 In Fig. 5 we have illustrated a modification of our fender adapted to be used with "grip-cars" of a cable-car system. In this form the notch L in the catch-bar J engages with the forward end of a horizontal slide-bolt R', which is longitudinally movable with respect 45 to the car in openings provided in two upwardly-extending projections M' and M² upon the upper side of the plate M and to the rear of the slot therein, in which is located the 50 catch-bar J. The slide-bolt R' is provided near its front end and to the rear of the projection M' with an annular flange, against which rests the forward end of a coil compression-spring N', which encircles the slide-bolt and the rear end of which has a bearing 55 against the forward side of the projection M². The slide-bolt is retracted from engagement with the notch in the rear edge of the catch-bar J by means of a rod R², the forward end 60 of which is secured to the rear end of the slide-bolt and the rear end of which is secured to the forward end of a bell-crank lever R³, which is pivoted near its center to a plate R⁴, which is secured to the car-floor.

65 To protect any person who is caught up by the fender from striking the front end of the car, we provide a supplemental fender. (Illus-

trated in Figs. 6 and 7.) This supplemental fender may or may not be used in connection with the fender we have already described. 70 When used in connection therewith, we prefer to have it raised and lowered conjointly with the main fender. In order to accomplish this, the forward end of each arm F' of the rock-shaft G has pivotally secured to it 75 one end of a rod G², the other end of which is secured pivotally to a curved arm G³, which extends forwardly from each end of a transverse rock-bar G', which is pivotally mounted in bearings secured to the car-sills X forward 80 of the rock-shaft G. The two arms G³ and the rock-bar G' support a rope or wire netting G⁴, which is stretched between them.

In operating our invention the fender is carried in the raised position, as shown in 85 Fig. 1. When it is desired to lower the forward end of the fender, the motorman or car-driver kicks the catch-bar J forward, releasing it from engagement with the plate M and permitting the rock-shaft G to rock in a 90 way such that the forward end of the fender will drop to or in close proximity to the track. Any obstacle struck by the fender when it is in the lowered position will be picked up by it and held from harm by the screenwork. 95 In operating the form shown in Fig. 5 the gripman presses his foot upon the bell-crank lever at its rear end, thus causing a withdrawal of the slide-bolt from engagement with the catch-bar J. The forward end of the 100 slide-bolt is rearwardly beveled, so that when the catch-bar is elevated it will be forced rearwardly without difficulty.

Where the supplemental fender is used, it 105 will be raised or lowered with the main fender, due to the connection between the arms G³ and the arm F'. The wedge R is used only when the motorman is at the other end of the car, at which time the danger of the catch-bar J being released is the greatest. 110

The car may be provided at each end with our fenders, if desired, where both ends of the car are at times forward ends.

Many modifications of our invention may be made without departing from its spirit. 115

Having thus described our invention, what we claim, and desire to secure by Letters Patent, is—

1. In a car-fender the combination with the frame A pivotally supported at its rear end to the car, of the rock-shaft G provided with the crank-arm H and the arms F' having the slots F, the posts E secured to the frame at one end and pivoted in the slots F at the other ends, the catch-bar J pivoted at one 120 end to the crank-arm H, and a locking mechanism adapted to engage the catch-bar so as to prevent rocking of the shaft G, substantially as described.

2. In a car-fender, the combination with a 125 frame provided with suitable screening and pivotally connected to the car at its rear end and free to swing up or down at its forward end, of a supplemental fender-frame pivot-

ally connected to the car at its rear end and free to swing at its forward end, a rock-shaft pivotally supported in bearings carried by the car, means for swinging the two frames 5 up or down when the rock-shaft is rocked in the proper direction, and a locking device for preventing the rock-shaft from rocking, substantially as described.

3. In a car-fender, the combination with a 10 frame provided with suitable screening and pivotally connected to the car at its rear end and free to swing up or down at its forward end, of a supplemental fender-frame pivotally connected at its rear end to the car and 15 free to swing up or down at its forward end, a rock-shaft provided with a crank-arm and pivotally supported in bearings secured to the car below the floor thereof, a bar pivotally connected at its lower end to the said 20 crank-arm and extending through the car-floor and vertically movable therethrough, and means for swinging the two frames up or down when the said bar is moved up or down, substantially as described.

25 4. In a car-fender, the combination with a frame pivotally connected with the car, of a rock-shaft provided with a central crank-arm and a crank-arm at each end, two posts connecting respectively the sides of the frame 30 with the two end crank-arms, a catch-bar pivoted at one end to the central crank-arm and extending therefrom to and through the car-floor, and a locking device for preventing vertical movement of the catch-bar, substantially 35 as described.

5. In a car-fender, the combination with a frame pivotally connected with the car, of a rock-shaft provided with a central crank-arm and a crank-arm at each end, two posts ex- 40 tending upwardly from the sides of the frame and pivotally connected at their upper ends

with the two end crank-arms respectively, a catch-bar pivoted at one of its ends to the central crank-arm and extending therefrom to and through the car-floor and provided 45 with a notch, and a locking device adapted to engage with the said notch for preventing vertical movement of the said catch-bar, substantially as described.

6. In a car-fender, the combination with a 50 frame pivotally connected with the car, of a rock-shaft provided with a central crank-arm and a crank-arm at each end, two posts connected at their lower ends to the frame and at their upper ends pivotally connected to the 55 two end crank-arms respectively, a catch-bar pivoted at one end to the central crank-arm and provided with a notch, and a spring-actuated locking device adapted to engage the 60 said notch for preventing vertical movement of the said catch-bar, substantially as described.

7. In a car-fender, the combination with a frame pivotally connected with the car, of a rock-shaft provided with a central crank-arm 65 and two end crank-arms, two posts extending upwardly one from each side of the frame and pivotally connected at their upper ends with the two end crank-arms respectively, an upwardly-movable catch-bar pivoted at one 70 end to the central crank-arm and extending to and through the car-floor, and a sliding bolt adapted to engage the catch-bar to prevent its downward movement, substantially as described.

In testimony whereof we affix our signatures in the presence of two witnesses.
